Primary Examiner — Philip S Hyder*(74) Attorney, Agent, or Firm* — The Rapacke Law Group, P.A.(57) **CLAIM**

The ornamental design for a reusable barrel grip, as shown and described.

DESCRIPTION

FIG. 1 is a perspective view of a reusable barrel grip showing the new design;

FIG. 2 is a front elevational view of the reusable barrel grip thereof;

FIG. 3 is a rear elevational view of the reusable barrel grip thereof;

FIG. 4 is a left side elevational view of the reusable barrel grip thereof;

FIG. 5 is a right side elevational view of the reusable barrel grip thereof;

FIG. 6 is a top plan view of the reusable barrel grip thereof; and,

FIG. 7 is a bottom plan of the reusable barrel grip thereof. The broken lines depict portions of the reusable barrel grip in which the design is embodied that form no part of the claimed design.
